UNITED STATES PATENT OFFICE.

FRANK LOWRY, OF LOUDONVILLE, OHIO, ASSIGNOR TO THE OHIO GREASE COMPANY,
OF LOUDONVILLE, OHIO, A CORPORATION OF OHIO.

GREASE-SUPERHEATER.

1,113,666.

Specification of Letters Patent.

Patented Oct. 13, 1914.

Application filed July 3, 1914. Serial No. 848,763.

To all whom it may concern:

Be it known that I, FRANK LOWRY, a citizen of the United States, residing at Loudonville, in the county of Ashland and State 5 of Ohio, have invented certain new and useful Improvements in Grease-Superheaters, of which the following is a specification:

The invention relates to means for superheating grease, oils and other kinds of lubricants for feeding the same into the supply 10 line or steam chest of an engine in proper form for attaining the most efficient lubrication; and the object of the improvements is to accomplish this purpose by a simple device 15 in which steam flowing from the supply line or steam chest is employed for superheating the grease, or other lubricant, and the grease or other lubricant is retarded in a coil surrounded by the superheating steam 20 a sufficient length of time to permit all of its particles to be superheated.

The object of the invention, thus briefly referred to, is attained by forming an upwardly extending coil in the grease tube adjacent 25 to the steam line; and by providing a chamber around the coil having communication directly with the steam line, as illustrated for a preferred embodiment of the invention in the accompanying drawings, 30 forming part hereof, in which—

Figure 1 is an elevation section of the improved superheater; Fig. 2, a plan section of the same on line 2—2, Fig. 1.

Similar numerals refer to similar parts 35 throughout the drawings.

In the improvement of the invention illustrated, the grease pipe 1 is connected by the union 2 with one end 3 of the differential T-fitting 4; the larger end 5 of which fitting is 40 connected with the steam line 6 by the short nipple 7, and the enlarged stem 8 of the fitting is connected with the lower end of the cylindric case 9, which case has the head 10 on its upper end to form the closed superheating chamber 11 opening only downward through the fitting 4 and the nipple 7 into the supply line 6. The grease tube 12 has one end connected in the smaller end 3 of the T-fitting whence it extends upward and 45 thence downward to form the inverted U-shaped coil 13 within the cavity of the superheating chamber 11, whence it extends freely through the nipple 7, and has its open end 14 located within the supply line 6. By this 50 simple construction and arrangement it is

evident that sufficient steam will flow from the steam line through the nipple 7 and upward into the superheating chamber 11, wherein it will superheat the coil 13 of the grease tube as well as the lubricant passing 60 through the same; it being understood that the water of condensation will flow by gravity downward from the superheating chamber and laterally through the nipple 7 back into the supply line. 65

In the operation of the device the grease or other lubricant is supplied or forced under pressure, either in a liquid, an atomized or a vaporized condition, through the grease pipe 1 from any suitable form of lubricant or feeding device; whence it is forced upward through the ascending branch of the coil 13 to the summit thereof, where it is met and retarded by the back pressure of the steam rising through the descending 75 branch of the coil from the supply line; and it is evident that the lubricant will be thoroughly heated by its passage through the coil of the grease tube and especially by reason of its retardation in the ascending 80 branch thereof. The trapping effect of the coil 13, caused by its location above its inlet and outlet ends, prevents the lubricant from being fed into the supply line by gravity and necessitates its being forced upward in a 85 solid column through the ascending branch of the coil, thereby subjecting it to the liquefying and vaporizing effect of the surrounding steam and causing it to be fed over and through the summit of the coil at 90 a rate corresponding to the increased pressure in the grease pipe over that in the supply line. 90

It is evident that the scope of the invention is not limited to the shaping of the coil as an inverted U as shown, the essential feature being that the coil, or some considerable portion thereof, is located above the inlet as well as the outlet ends thereof, and that the same should be located within a superheating chamber adjacent to the steam line, which is preferably heated with steam flowing upward into the chamber therefrom. 100

I claim:

1. A steam supply line, an adjacent heating chamber communicating therewith, and a grease tube leading into the supply line and having a coil extending above its inlet and outlet ends into the heating chamber. 105
2. A steam supply line, an adjacent heat- 110

ing chamber communicating at its lower end therewith, and a grease tube passing through the lower end of the heating chamber into the steam supply line and having a coil extending upward into the heating chamber.

3. A steam supply line, an adjacent heating chamber communicating at its lower end therewith, and a grease tube passing through the lower end of the heating chamber into the steam supply line and having an inverted U-shaped coil extending upward into the heating chamber.

4. A steam supply line, an adjacent heating chamber, a nipple connecting the lower end of the chamber with the supply line, and a grease tube extending through the

lower end of the heating chamber and the nipple into the supply line and having a coil extending upward into the heating chamber.

20

5. A steam supply line, an adjacent heating chamber, a nipple connecting the lower end of the chamber with the supply line, and a grease tube extending through the lower end of the heating chamber and the nipple into the supply line and having an inverted U-shaped coil extending upward into the heating chamber.

25

FRANK LOWRY.
